We claim the ornamental design for a battery pack, as shown and described.

DESCRIPTION

FIG. 1 is a front perspective view of a battery pack showing our new design in a first embodiment.

FIG. 2 is a first side view of the battery pack of FIG. 1.

FIG. 3 is a second side view of the battery pack of FIG. 1.

FIG. 4 is a top view of the battery pack of FIG. 1.

FIG. 5 is a bottom view of the battery pack of FIG. 1.

FIG. 6 is a front view of the battery pack of FIG. 1.

FIG. 7 is a rear view of the battery pack of FIG. 1.

FIG. 8 is a front perspective view of a battery pack showing our new design in a second embodiment.

FIG. 9 is a first side view of the battery pack of FIG. 8.

FIG. 10 is a second side view of the battery pack of FIG. 8.

FIG. 11 is a top view of the battery pack of FIG. 8.

FIG. 12 is a bottom view of the battery pack of FIG. 8.

FIG. 13 is a front view of the battery pack of FIG. 8; and,

FIG. 14 is a rear view of the battery pack of FIG. 8.

The broken lines in the figures depict portions of the battery pack which form no part of the claimed design.
